UNITED STATES PATENT OFFICE.

HENRY W. ARMSTRONG, OF NEW HAVEN, CONNECTICUT.

DESIGN FOR A TWEEZER.

58,208.

Specification for Design.

Patented June 28, 1921.

Application filed March 11, 1921. Serial No. 451,592. Term of patent 14 years.

To all whom it may concern:

Be it known that I, HENRY W. ARMSTRONG, a citizen of the United States, residing at New Haven, in the county of New Haven and State of Connecticut, have invented a new, original, and ornamental Design for a Tweezer, of which the following is a specification, reference being had to the accompanying drawing, forming part thereof.

The figure is a perspective view of a tweezer showing my new design.

I claim:

The ornamental design for a tweezer as shown.

HENRY W. ARMSTRONG.

Witnesses:

FREDERIC C. EARLE,
MALCOLM P. NICHOLS.
